MOUNTING STRUCTURE FOR WINDOWS

Claude C. Brooks, Kansas City, Mo.

Application April 7, 1947, Serial No. 739,772

3 Claims. (Cl. 189—76)

1

This invention relates generally to the field of building and construction and particularly to a mounting assembly for closures, the primary aim being to provide mounting structure for closure panels such as window panes, screens and the like having a novel sectional frame for removably holding the panel in operative relationship thereto.

The most important object of this invention is to provide a mounting structure for screens or window panes having a frame comprised of a pair of sections, one of the sections being provided with a continuous channel or groove for receiving a complementary section made from tubular members, the said tubular section holding the panel against the first mentioned channeled section when in operative use.

Another important object of this invention is to provide mounting structure for closure panels having a sectional frame, one of the sections comprising a plurality of interconnected tubular members circumscribing the panel and each provided with a longitudinal slot to receive a proximal marginal edge of the panel for holding the latter against the other section of the frame.

A further object of this invention is to provide a mounting structure for window panes, screens or the like wherein the aforesaid tubular section of the frame fits tightly within the corresponding channels formed in the other section of the frame and held therein by a plurality of elements passing through the bottom wall of the section forming said groove.

A still further object of this invention is the provision of mounting structure for window screens or other flexible closure panels having a frame made from a pair of complementary interfitting sections, the marginal edges of said screen being interposed between the sections and held in tight stretched relationship when the sections are fitted together.

Other objects of this invention include the manner in which the section of the frame formed from a plurality of tubular members presents a dead-air space circumscribing the panel to aid in positively sealing entrance of air and other elements; the way in which the tubular members tightly fit within the walls of the other section forming the channel thereof; and the manner in which the tubular section of the frame holds the closure panel tightly against the longitudinal edge of one wall forming the channel of the other section to present a still further sealing against entrance of the elements.

Many minor objects of this invention will be

2

made clear or become apparent during the course of the following specification, reference being had to the accompanying drawing, wherein:

Fig. 1 is a side elevational view of a mounting structure for screen and window panes made in accordance with my present invention, parts being broken away to reveal details of construction.

Fig. 2 is a side elevational view thereof showing the side of the mounting structure opposite to that shown in Fig. 1.

Fig. 3 is a cross sectional view taken on line III—III of Fig. 1; and

Fig. 4 is a fragmentary cross-sectional view similar to that shown in Fig. 3 and illustrating a modified form of mounting structure for closure panels.

This application relates to my co-pending application, now abandoned, filed under even date herewith, Serial No. 739,771, covering Combination Storm Window and Screen, and covers the manner of constructing the casement per se illustrated in said co-pending application.

The casement or window chosen for illustration is formed principally for use as a storm window or screen and is broadly designated by the numeral 10. This window 10 may be mounted within a suitable frame in any manner by a bracket assembly as shown and described in the above mentioned co-pending application, or may be hingedly mounted or fitted within the supporting frame therefor in any of the conventional manners.

In the modification illustrated in Figs. 1 to 3 inclusive, the frame for mounting the closure panel or glass pane 12, is sectional and broadly designated by the numeral 14. One section of the frame 14 designated by the numeral 16 constitutes a plurality of members formed in cross section as illustrated in Fig. 3 and mitered at their respective ends to present a polygonal framework in the usual manner. The individual members forming this section 16 are substantially I-shaped in cross section as shown in Fig. 3 but may be made simply U-shaped in cross section to present at least one channel 18 extending longitudinally along one face thereof.

This channel 18 has a pair of legs 20 and 22 and a bight portion 24 to present three walls 50 forming the channel 18. The other section of frame 14 designated by the numeral 26 comprises a plurality of tubular members mitered at their ends or otherwise interconnected to provide a polygonal frame circumscribing the window pane 12.

Each of the tubular members forming the section 26 of frame 14 is provided with a longitudinal slot 28 for receiving the proximal marginal edge of the pane 12. This slot 28 is coextensive in length with the respective tubular member forming a part of the section 26 and has a width substantially the same as the width of the pane 12 to the end that a tight fit is presented between the sides of slot 28 and the pane 12 when the latter is extended into slot 28 and into the interior of the respective tubular members.

The width of the channel 18 in each of the I-shaped members forming section 16 is substantially the same as the outside diameter of each of the tubular member forming section 26 to the end that a tight fit is presented when a section 26 is fitted into the channel 18 of the section 16. By the same token, the distance between the innermost face of wall 24 of the members forming section 16 and the outermost longitudinal edges of the walls 20 and 22 respectively, is substantially the same as the distance between the face of pane 12 adjacent section 16 and the proximal edge of the section 26 within the channel 18. In other words, when the tubular members forming section 26 are within the groove 18, these tubular members are in tight contacting engagement with the walls 20, 22 and 24 of the section 16 forming the channel 18.

A plurality of screws or the like 30 pass through the wall 24 of each of the members forming section 16 into screw-threaded engagement with the tubular members forming section 26 as illustrated in Fig. 3, and when these screws 30 draw the sections 16 and 26 of frame 14 tightly together where the section 26 is against the wall 24 of section 16, one face of the pane 12 is tightly against the longitudinal edge of the wall 22.

It is clear from the foregoing that a plurality of positive seals are presented when the sections 16 and 26 are formed and fitted as above described. One of these seals is the tight engagement between the pane 12 and the longitudinal edge of the wall 22. Another seal is the 3-point engagement between the section 26 and the walls 20, 22 and 24 respectively of the section 16 of frame 14. Another seal is presented by the tight fit between the pane 12 and the slot 28 formed in the tubular members of section 26 and finally, a dead-air space is presented in circumscribing relationship to the pane 12 by the interior of the tubular members themselves forming the section 26.

Fig. 2 of the drawing illustrates the manner in which the I-shaped members forming section 16 of frame 14 are held together through the medium of a plurality of L-shaped brackets 32 riveted or otherwise secured as at 34 to the respective members forming section 16 and disposed at the point of miter at each of the four corners of the polygonal frame 14. No direct interconnection is made between the four tubular members defining the section 26 of frame 14, this section 26 being held together through the medium of the screws 30 which join sections 16 and 26 as aforesaid.

It is notable therefore, that removal of the plurality of screws 30 and all of the members forming section 16 will permit removal of the section 26 and the pane 12 as a body for replacement of the pane 12 in the event the same becomes broken.

Again, as above set forth, it is understood that the I-shaped members of section 16 need only have one channel member 18, the opposite face thereof being smooth and the screws 30, as well

as the brackets 32, countersunk to provide means for any desired type of fastening of the window 10 within its supporting framework.

In the modified form illustrated in Fig. 4 of the drawing, the frame 100 is made from a pair of complementary sections 102 and 104 in virtually the same manner as frame 14 illustrated in Figs. 1 to 3 inclusive. In this instance, however, a screen or other flexible closure panel 106 is held in operative relationship within the frame 100. The slots 28 in the tubular members shown in Fig. 3, are eliminated in the modification shown in Fig. 4 and the screen 106 is interposed between the sections 102 and 104. The marginal edge of this screen 106 extends into the slot 108 formed in the I-shaped members forming a part of the section 102. These marginal edges of the screen 106 are disposed in partial circumscribing relationship to the tubular members forming the section 104 and are held in tight engagement with the section 102 by the section 104. In other words, the screen 106 is held tightly against all the three walls forming the section 108 when screws 110 are used to interconnect sections 102 and 104 in the same manner as above described with respect to Figs. 1 to 3 inclusive.

It is notable that here again, the screen 106 may be entirely removed and replaced or repaired by the simple expedient of removing the plurality of screws 110. Furthermore, it is to be noted that when screen 106 is mounted between the sections 102 and 104 of frame 100, the drawing together of these sections 102 and 104 by the screws 110, will tend to stretch the screen 106 to an extremely tight condition.

The importance of this last mentioned feature will become obvious to those skilled in the art since it is generally known that one of the most difficult problems in the construction of screens and framework therefor, is that of holding the screen 106 in a tight condition and maintaining such condition throughout the life of the screen 106, as well as the framework therefor.

While the channel 18 of section 20 of frame 14 is shown as being substantially centrally disposed in one face of the members forming section 20, this feature is not critically essential to this structure. That portion of these members forming the wall 20 for instance may be made considerably wider for instance to present a wider border circumscribing the section 26 or along any side thereof as desired.

While many advantages of the mounting structure for screens and window panes forming the subject matter of this invention have been set forth above, it is understood that many additional advantages will emanate through use of the mounting structure and it is, therefore, understood that those so made possible are contemplated hereby.

Having thus described the invention, what is claimed as new and desired to be secured by Letters Patent is:

1. A closure comprising a pair of frame sections; a panel carried by one of the said sections, the other section having a portion for receiving the one section, said portion being substantially U-shaped in cross section, including a bight and a pair of laterally-extending legs, and presenting a channel, said one section being tubular and having a slot formed in the innermost edge thereof, said panel extending into said slot and having the marginal edges thereof within the one section with the latter circumscribing the panel; and joining means for holding the

frame sections together with the one section extending into said channel and partially embraced thereby, said means being adapted to draw the panel into tight, line-contact engagement with the outermost free edge of one of said legs as the same holds the sections together.

2. A closure comprising a pair of frame sections; a panel carried by one of said sections, the other section having a portion for receiving the one section, said portion being substantially U-shaped in cross section, including a bight and a pair of laterally-extending legs, and presenting a channel, said one section being tubular and having a slot formed in the innermost edge thereof, said panel extending into said slot and having the marginal edges thereof within the one section with the latter circumscribing the panel; and joining means for holding the frame sections together with the one section extending into said channel and partially embraced thereby, said means being adapted to draw the panel into tight, line-contact engagement with the outermost free edge of one of said legs as the same holds the sections together, said one section being in tight engagement with the legs and the bight of said portion of the other section.

3. A closure comprising a pair of frame sections; a panel carried by one of the said sections, the other section having a portion for receiving the one section, said portion being substantially U-shaped in cross section, including a bight and a pair of laterally-extending legs, and

presenting a channel, said one section being tubular and having a slot formed in the innermost edge thereof, said panel extending into said slot and having the marginal edges thereof within the one section with the latter circumscribing the panel, said panel being tightly fitted within said slot; and a number of fasteners passing through said bight and connecting with the one section, said fasteners being adapted to draw the one section into the channel in tight engagement with said legs and the bight of said portion of the other section and to hold the panel in tight, line-contact engagement with the free, outermost edge of one of said legs.
